COMBINED CABINET AND BENCH

Napoleon Lintereur, Two Rivers, Wis., assignor to Hamilton Manufacturing Company, Two Rivers, Wis., a corporation of Wisconsin

Application February 9, 1959, Serial No. 54,512

Term of patent 14 years

(Cl. D16—2)

Figure 1 is a front elevational view of a combined cabinet and bench showing my new design;

Figure 2 is a fragmentary section taken on the line 2—2 of Fig. 1; and

Figure 3 is a top plan view.

The back of the assembly is conventionally plain.

I claim:

The ornamental design for a combined cabinet and bench, substantially as shown and described.
